UNITED STATES PATENT OFFICE.

JOSEPH W. STILLWELL, OF NEW YORK, N. Y.

STEAM-BOILER FURNACE.

SPECIFICATION forming part of Letters Patent No. 764,314, dated July 5, 1904.

Application filed October 16, 1903. Serial No. 177,256. (No model.)

To all whom it may concern:

Be it known that I, JOSEPH W. STILLWELL, a citizen of the United States, residing in the city of New York, borough of Brooklyn, county of 5 Kings, and State of New York, have invented certain new and useful Improvements in Steam-Boiler Furnaces, of which the following is a specification sufficient to enable others skilled in the art to which the invention app- 10 pertains to make and use the same.

My present invention relates to means for effecting the perfect combustion of all the inflammable constituents of fuel used in heating a steam-boiler, thereby preventing the formation 15 of smoke, as set forth in my application for patent, Serial No. 145,704, filed March 2, 1903, and allowed June 27, 1903; and the invention consists in the special construction and arrangement of parts hereinafter de- 20 scribed and claimed specifically whereby the apparatus is rendered more durable and effective in operation.

In the accompanying drawings, Figure 1 is a vertical sectional elevation of a boiler-furnace constructed according to my invention. Fig. 2 is a transverse vertical section upon plane of line 2 2, Fig. 1, looking toward the front end of the furnace. Fig. 3 is a similar section upon plane of line 3 3, Fig. 1, looking 25 rearward. Fig. 4 is a sectional view of one of the telescopic joints in the conduit. Fig. 5 is a sectional view of the mouth of a conduit, taken upon plane of line 5 5, Fig. 1. Fig. 6 is a horizontal section upon plane of 30 line 6 6, Fig. 1, the boiler being omitted. Fig. 7 is a horizontal section upon plane of line 7 7, Fig. 1, showing the conduit-pipe, &c., in elevation; Fig. 8, a front elevation of the upper portion of the furnace; Fig. 9, a 35 sectional detail of one of the induction-jets; Fig. 10, a sectional detail of the upper jet and deflector.

It is to be understood that the main parts of the apparatus hereinafter described are 40 preferably duplicated on opposite sides of the furnace and boiler, as in my previous application for patent hereinbefore referred to, like letters of reference in the drawings referring to like parts on either side of the 45 boiler.

The furnace-walls or brickwork is lettered A and sustains a horizontal tubular boiler B. F is the fire-box or combustion-chamber, into which the fuel is introduced in the usual manner.

The products of combustion from the fire-box F pass over the bridges *a a'*, through the tubes *b* of the boiler B, and into the passage *c*, which leads to the chimney C. In the passage *c* between the boiler-tubes *b* and the chimney C is interposed the open flaring mouth *e* of the conduit-pipe E, which extends to the fire-box F, so that the products of combustion drawn into the open mouths *e* may be returned directly to the said fire-box. I effect this return of products of combustion to the fire-box by the injection of steam into the lower horizontal extension of the conduit E in the direction of the fire-box, so that an induced current is created within the conduit 60 E, as in my former application, by the use of a jet G. I have found by experience and experiment, however, that I can obtain better, quicker, and more positive results by using a supplementary jet H at the mouth *e* of the 65 conduit, and this construction constitutes one of the features of my present invention, the induced current created by the jet G through the vertical extension of the pipe E being aided and abetted by the pressure created by 70 the supplementary jet H within the upper horizontal member of the conduit E. The proximity of the supplemental jet to the up-take-passage *c* aids materially in diverting the products of combustion rising from the 75 boiler-tubes into the conduit E.

The conduit E where it passes below the boiler is supported in such manner as to be exposed directly to contact with the products of combustion passing from the fire-box to 80 the rear of the boiler. To this end I support it upon a shelf *a'*, projecting from the inner side wall of the furnace, said shelf being constituted of fire-bricks built into the side wall and formed with upwardly-projecting flanges 85 *a'*, which sustain the conduit laterally in position upon the shelf *a'*, as will be understood by reference to Fig. 2. The lower extension of the conduit E being also exposed to intense heat, I make provision for avoiding the strain 90

and rupture that would otherwise occur by making this lower section or extension of the conduit E in two parts united in the form of a telescopic joint ϵ^2 , I having found by actual experience that the lower horizontal section of the conduit E soon becomes useless unless provision is thus made to have the parts of the conduit slide freely one upon the other. This feature of my invention is the result of 10 careful investigation and experiment, and by it I greatly lengthen the life and usefulness of the conduit. In fact, while the return-conduits and connections as heretofore constructed and used by me have been practical 15 and operative the need of frequently replacing the lower extension of the conduit has been a serious difficulty, which I have at last overcome by the means herein set forth. While not so essential as in the case of the 20 lower extension of the conduit E, the upper horizontal section of the said conduit, as indicated in Figs. 1 and 7 of the drawings, (and even the vertical portion of the conduit,) may, if so desired, be thus protected against the 25 effects of expansion and contraction.

Another feature of novelty in my present structure consists in the use of one or more relatively broad flat nozzles ϵ^3 at the extremity of the conduit E within the fire-box arranged 30 to discharge the returned products of combustion over the grate-bars and toward the rear of the furnace, as will be readily understood by reference to Figs. 1, 2, and 6. By this means I attain an even uniform distribution 35 of such returned products of combustion over the bed of incandescent fuel upon the grate, and thereby insure the reduction of all unconsumed carbon and other inflammable products of combustion withdrawn by the 40 conduit E from the uptake-passage c.

The steam-pipe i for conducting steam under pressure to the induction-jet G is exposed to the contact with the products of combustion, as in my former construction, for the 45 purpose of superheating the steam injected into the lower horizontal member of the conduit E by the jet G. I prefer also to superheat the steam injected by the forcing-jet H into the upper horizontal member of the conduit E and for this reason pass the steam through a superheating drum or chamber D, situated in the uptake-passage c, where it is exposed to direct contact with the hot products of combustion escaping from the forward 50 ends of the boiler-tubes.

Steam may be supplied to the pipe i, passing to the induction-jet G and to the drum D or the pipes d, connecting directly with the force-jet H either from the steam-drum b' of 60 the boiler or from an independent source by means of suitable piping.

Where the described return-conduit E and connections are duplicated upon opposite sides of the boiler, as is usually preferable in practice under ordinary conditions of use, I em-

ploy what may be designated as an "inverted" deflector L, extending between the two mouths e of the return-conduits E for the purpose of intercepting the products of combustion escaping from the boiler-tubes toward the chimney and directing the said products so intercepted into the return-conduits E. This deflector is concave on its under side and is preferably depressed centrally, converging upward in opposite directions, 75 with its extremities extending directly into the mouths e e of the conduits E E. By its use a much larger percentage of unconsumed products of combustion is returned to the fire-box. 80

What I claim as my invention, and desire to secure by Letters Patent, is—

1. The combination of a steam-boiler and furnace, the uptake-passage, return-conduits situated upon opposite sides of the boiler and adjacent to the inner side walls of the furnace, said conduits being formed with mouths and the other extremities of said return-conduits extending and opening into the fire-box in close proximity to the grate, steam-jets in proximity to the mouths of said conduits arranged to force products of combustion into said conduits, other steam-jets situated in proximity to the uptake-passage and between said forcing-jets and the fire-box 95 and arranged to create an induction in said return-conduits, and oppositely-inclined deflectors extending between the mouths of the return-conduits in the passage between the boiler-tubes and the chimney, arranged to intercept products of combustion and guide them into the mouths of the said return-conduits for the purpose described.

2. The combination of a steam-boiler and furnace, the uptake-passage, return-conduits situated upon opposite sides of the boiler and adjacent to the inner side walls of the furnace, said conduits being formed with mouths opening into the passage between the boiler-tubes and the chimney, the other extremities of said return-conduits extending and opening into the fire-box in close proximity to the grate, steam-jets in proximity to the mouths of said conduits, other steam-jets situated in proximity to the uptake-passage and between 105 said forcing-jets and the fire-box and arranged to create an induction in said return-conduits, and oppositely-inclined deflectors connecting the mouths of the return-conduits in the passage between the boiler-tubes and the chimney, arranged to intercept products of combustion and guide them into the mouths of said return-conduits, and a steam-drum in the passage 110 between the boiler-tubes and the chimney, arranged to supply superheated steam to the forcing-jets in the mouths of the said return-conduits, as and for the purpose set forth.

3. The combination of a steam-boiler and furnace, a return-conduit arranged adjacent to the side walls of the furnace with a mouth 130

opening into the passage between the boiler-tubes and the chimney, the other end of said return-conduit opening into the fire-box in close proximity to the grate, a shelf of fire-brick supporting said return-conduit under the boiler, said shelf being formed with a retaining-flange as described, and means for in-

jecting steam under pressure into said return-conduit in the direction of the fire-box for the purpose set forth.
